UNITED STATES PATENT OFFICE.

HENRY W. BRENT, OF BALTIMORE, MARYLAND.

OIL-BURNER.

1,313,059.

Specification of Letters Patent.

Patented Aug. 12, 1919.

Application filed January 7, 1919. Serial No. 270,056.

To all whom it may concern:

Be it known that I, HENRY W. BRENT, a citizen of the United States, residing at Baltimore, State of Maryland, have invented 5 certain new and useful Improvements in Oil-Burners, of which the following is a specification.

This invention relates to certain new and useful improvements in burners of oil stoves 10 and it has for a leading object to improve the construction of the burner and the adjustment of the wick so as to minimize the danger of fire and maintain the wick, whether visible or invisible, at such position 15 that there will result a fine blue flame under normal working conditions; the arrangement being such that the wick may be adjusted the right position to attain the desired result and without necessarily requiring inspection of the flame and by a simple 20 single movement of an operating mechanism.

The present invention is an improvement 25 of the oil burner disclosed in my former Patent No. 1,082,796, dated December 30, 1913, although the salient features of the wick operating mechanism may be employed with other types of burners without departing 30 from the spirit of my invention.

With the above and other objects in view 35 my invention consists of the parts and the constructions, and arrangements and combinations of parts which I will hereinafter describe and claim.

In the accompanying drawing forming 40 part of this specification, and in which similar reference characters indicate like parts in the several views;—

Figure 1 is a side elevation of a burner 45 tube embodying my invention, showing a portion of the tube broken away.

Fig. 2 is a top plan view of the same.

Fig. 3 is a longitudinal sectional view of 45 the wick adjusting and controlling mechanism, on the line 2—2 of Fig. 2.

Fig. 4 is a cross sectional view on the line 4—4 of Fig. 1.

Fig. 5 is a side view of the hand wheel, 50 and a fragment of the upper portion of the tube, 11, and shaft, 12.

In carrying out my invention I may use 55 the present improvements in connection with the different types of burners, either with or without the usual spreader-plates, but for illustrative purposes I have shown said im-

provements as applied to the type of burner disclosed in my aforesaid prior patent, and which burner usually has a spreader-plate 60 surmounting the burner tube, as shown by dotted lines in Fig. 1. The particular means for supporting and adjusting the spreader-plate form no essential part of the present invention and hence they are not disclosed, 65 but it will be understood that any well known and appropriate means, such for instance as disclosed in said former patent, may be used if desired.

The burner tube A, is preferably formed 70 with concentric inner and outer walls, joined at the bottom and adapted to inclose between them a circular flat wick, A', the space between the inner and outer walls of the burner tube forming a font or receiver, to which oil is supplied through a connection a, in the usual manner.

On the outside of the burner is a housing, 10, from which extends upwardly at 75 an angle a tube, 11, which forms a long bearing for a wick-operating shaft, 12, on the lower end of which, within the housing 80 and operating through a slot in the outer wall of the burner tube are toothed wheels, 13, which are designed to engage the wick to raise and lower the same in a manner well known in this art, said shaft having 85 at its upper and outer end a rotatable and reciprocable hand wheel, 14, or other device by which the shaft may be turned to adjust the wick and the construction and operation of which hand wheel I will hereinafter more 90 fully describe.

Fixedly secured to the sleeve or tube 11, and extending substantially at right-angles thereto, is a plate or sector, 15, provided with suitable indicating marks or graduations, 16, 95 17, over which is designed to operate a pointer, 18, fixedly secured to and extending from a ratchet wheel, 19, which is loosely mounted on the tube, 11, between appropriate collars, 20, or in an equivalent 100 annular groove formed in said tube, the said ratchet wheel having secured to it one end of a coiled spring, 21, the opposite end of which is in turn fixed to a pin, 22, on the stationary tube, 11, and which spring serves 105 to return the ratchet wheel to normal position after it has been turned, say to the left, for the purpose of lowering the wick, the spring being placed under tension during this turning of the ratchet wheel and which 110

turning is effected through the hand wheel, 14, and suitable connections which I will presently describe.

One face of the ratchet wheel is provided 5 with a pin or stud, 23, and on the tube, 11, is a pin or stud, 24, with which the pin of the ratchet-wheel is adapted to contact during a certain period of rotation of the wick-operating shaft, the ratchet-wheel being 10 slotted at a point between the aforesaid pins, as shown at 25, to admit one end of a small spring, 26, which is designed to normally bear against the pin, 24; the other end of the spring is secured to the opposite face 15 of the ratchet-wheel, and the two pins being arranged to form a stop to limit the turning of the wick raising shaft to the right beyond a predetermined point, and the consequent predetermined elevation of the wick to such 20 point that the desired blue flame is obtained.

Secured to the wick raising shaft, 12, is a bracket or arm, 27, the outer end of which is forked to receive a lever, 28, which is pivoted within the forked portion of the bracket 25 and has its lower end formed as a pawl, 29, adapted to engage and disengage the teeth of the ratchet-wheel, 19; the upper end of the pivoted lever, 28, extending along the shaft and being substantially cam-shaped, 30 or inclined outwardly, and being slidably guided in an opening formed in a disk, 30, on a sleeve, 31, which is rigid with and spaces the disk from the hand-wheel, 14, said sleeve being slotted on both sides, to receive a cross pin, 32, carried by the wick-raising shaft and serving to guide the sleeve and its attached hand-wheel and disk in a direction longitudinal of the shaft, the length of the slot determining the distance 40 which the hand wheel may be reciprocated relatively to the shaft, and the pin, 32, serving, also, as a means for transmitting rotary movement from the hand-wheel to said shaft.

45 As before stated, both sides of the sleeve, 31, are slotted to receive the cross pin, 32, and the head of this pin is designed to contact with a spring-plate, 33, secured to the sleeve and serving, by bearing against the 50 head of the pin, to frictionally hold the slotted sleeve and the hand-wheel and attached parts at the limit of the outer and inner reciprocal movement thereof, thereby overcoming the liability of the accidental displacement or change of position of the hand wheel relatively to the shaft, and the unlocking of the locked ratchet wheel, after 55 said wheel has been moved in either of its two directions, in or out, it being understood that when the hand-wheel is being 60 pulled outwardly on the wick-raising shaft, the inclined or cam-end of the lever, 28, will be moved inwardly thereby rocking the lever about its pivot and lifting the pawl-end of 65 said lever out of its connection with the

ratchet wheel, and allowing this wheel, which I now assume has been rotated and is under the tension of the spring, 21, to be returned to normal position by said spring.

When the hand-wheel is pulled outwardly 70 on the shaft it is held in that position by a bowed portion of the spring, 33, and with the pawl, 29, out of engagement with the teeth on the ratchet-wheel, and the wick-raising shaft may now be freely rotated 75 either to the right or to the left, to accordingly raise or lower the wick as desired, without communicating rotary motion to the ratchet-wheel. When the hand wheel is pushed inwardly the cam-end of the lever, 80 28, rides in contact with the wall of the opening in the disk, 30, and the lever is caused to turn on its pivot and its pawl-end to be forced into engagement with the teeth on the ratchet-wheel; a bowed portion of the 85 spring, 33, will now hold the hand-wheel and its adjuncts in this position and against accidental movement in an outward direction.

In operating the device, say, for illustration, when because of consumption of the 90 wick the position of the latter must be changed to insure proper combustion, the hand-wheel is pulled outwardly and the wick operating shaft is turned, through the hand wheel, to bring the top edge of the wick at 95 such distance above the burner tube, A, that the now projecting carbonized portion of the wick may be removed by a wiping action, or otherwise. Then, when the hand-wheel is pressed inwardly, the pawl, 29, is caused to engage the teeth on the ratchet wheel, thus locking the latter to the shaft, 12. The hand-wheel may now be turned to the right only until the stop pins, 23, and 24, 100 come into contact as further movement of the ratchet-wheel in the same direction and consequently a further rotation of the wick-raising shaft cannot possibly occur. In the meantime, the pointer, 18, has been moved from the point, 16, on the plate, 15, to the 105 point 17, the distance between these two points indicating the proper elevation of the wick above the top of the burner tube, A. Thus there is provided a fixed and predetermined stop and a visual indication, independent of observation of the flame itself, 110 of the extent to which the wick has been raised, and a positive means for insuring the elevation of the wick only to such point that the desired blue flame can be obtained and 115 maintained. Of course, the wick may be turned down, say, to extinguish the flame by turning the operating shaft to the left since there are no stop-means employed for limiting rotation in that direction, except that 120 not more than a complete rotation is possible even to the left because of the presence of the aforesaid contact pins, 23, 24.

The foregoing provides a simple means for limiting the wick raising function to 130

only a short distance, in one direction, for burning purposes, and providing for a more extended wick-lowering action, in another direction, it being understood that at the 5 conclusion of partial rotation in either direction, the hand wheel and its associated parts may be slid outwardly on the operating shaft to thus trip the pawl and release the loose ratchet wheel from fixed connection with the shaft. As soon as this occurs the coiled spring, 21, returns the ratchet wheel to normal position and the pointer to the starting point, indicated at 16; the wick-operating shaft in the meantime remaining 10 undisturbed.

Having thus described my invention what I claim as new and desire to secure by Letters Patent is:—

1. In an oil burner, the combination with 20 a burner tube adapted to contain a wick, of wick-operating means having the capacity of positively stopping the elevation of the wick during a complete movement of said means in one direction so as to set the wick 25 at a fixed and predetermined maximum height above said tube, and automatically operating means for resetting the wick operating means.

2. In an oil burner, the combination with 30 a burner tube adapted to contain a wick, of wick-operating means having the capacity of positively stopping the elevation of the wick during a complete movement of said means in one direction so as to set the wick 35 at a fixed and predetermined maximum height above said tube, means independent of the flame for visually indicating the extent of said wick elevating movement, and means for automatically resetting the wick 40 operating means.

3. In an oil burner, the combination with 45 a burner tube adapted to contain a wick, of wick elevating and lowering means and other means co-acting with the first named means for positively stopping the elevation of the wick at a fixed and predetermined height above the top of the burner tube, and spring actuated means for automatically resetting the wick operating means.

50 4. In an oil burner, the combination with a burner tube adapted to contain a wick, of a wick raising and lowering shaft, a spring actuated member loose relative to the shaft, co-acting stops one of which is carried by 55 said member adapted to limit the rotation of said member to a predetermined and substantially short distance in the wick-raising direction and thereby fix the maximum height of the wick in its burning position, 60 and selective means for connecting and disconnecting said member and the wick-actuating shaft.

5. In an oil burner, the combination with 65 a burner tube, adapted to contain a wick, of a wick raising and lowering shaft, a ratchet-

wheel circumscribing the shaft and loosely mounted relatively thereto, co-acting stops one of which is fixed and the other is carried by said ratchet-wheel, said stops adapted to limit the rotation of the wheel to a predetermined and substantially short distance in the wick raising direction, to thereby fix the maximum height of the wick in its burning position, and selective means for connecting and disconnecting said wheel and the wick raising shaft.

6. In an oil burner, the combination with a burner tube adapted to contain a wick, of a wick raising and lowering shaft, a member concentric with the shaft and loosely mounted relatively thereto, co-acting stops one fixed and the other on said wheel, said stops normally separated a distance substantially equal to the maximum distance the wick can move in one direction and said stops adapted to contact to prevent the elevation of the wick beyond a predetermined maximum height, and selective means for connecting and disconnecting said ratchet-wheel and the wick actuating shaft.

7. In an oil burner, the combination with a burner tube adapted to contain a wick, of a wick raising and lowering shaft, a ratchet-wheel concentric with the shaft and loosely mounted relatively thereto, a spring connecting with the wheel adapted to return the same to a normal position after said wheel has been partially rotated in one direction, co-acting stops one of which is carried by said wheel adapted to limit the rotation of the wheel to a predetermined and substantially short distance in the wick raising direction and thereby fix the maximum height of the wick in its burning position, and selective means for connecting and disconnecting said wheel and the wick actuating shaft.

8. In an oil burner, the combination with a burner tube adapted to contain a wick, of a wick raising and lowering shaft, a ratchet wheel concentric with the shaft and loosely mounted relatively thereto, a spring connecting with the wheel adapted to return the same to a normal position after said wheel has been partially rotated in one direction, co-acting stops one of which is carried by said wheel adapted to limit the rotation of the wheel to a predetermined and substantially short distance in the wick raising direction and thereby fix the maximum height of the wick in its burning position, 110 selective means for connecting and disconnecting said wheel and the wick actuating shaft, said selective means comprising a pivoted lever having at one portion a pawl to removably engage the ratchet wheel and having another portion serving as a cam, and a part slidably mounted on the shaft and actuating said lever to lift the pawl out of engagement with the ratchet wheel and disconnect the wheel with the shaft when said part 115 120 125 130

- is longitudinally moved in one direction, and to connect the pawl with said ratchet wheel when said part is moved in another direction.
5. In an oil burner, the combination with a burner tube adapted to contain a wick, of a wick raising and lowering shaft, a ratchet wheel concentric with the shaft and loosely mounted relatively thereto, a spring connecting with the wheel adapted to return the same to a normal position after said wheel has been partially rotated in one direction, co-acting stops one of which is carried by said wheel adapted to limit the rotation of 10 the wheel to a predetermined and substantially short distance in the wick raising direction and thereby fix the maximum height of the wick in its burning position, selective means for connecting and disconnecting said 15 wheel and the wick actuating shaft, said selective means comprising a pivoted lever having at one portion a pawl to removably engage the ratchet wheel and having another portion serving as a cam, a part slidably 20 mounted on the shaft and actuating said lever to lift the pawl out of engagement with the ratchet wheel and disconnect the wheel with the shaft when said part is longitudinally moved in one direction, and to connect 25 the pawl with said ratchet wheel when said part is moved in another direction, and a cross pin extending through the shaft and said sliding part and permitting the same to be rotated in unison.
- 30 35. 10. In an oil burner, the combination with a burner tube, adapted to contain a wick, of a wick raising and lowering shaft, a ratchet wheel concentric with the shaft and loosely mounted relatively thereto, a coiled spring 40 connecting with the wheel adapted to be wound when the wheel is turned in one direction, and to unwind and return the wheel to normal position, said wheel having a

pointer, an indicating plate over which the pointer operates, said plate having indicating marks thereon, co-acting stops one of which is carried by said wheel adapted to limit the rotation of the same to a predetermined and substantially short distance in the wick raising direction to thereby fix the maximum height of the wick in its burning position, a spring connected to the wheel adapted to separate the stops and rotate the wheel to return the pointer to zero position, means including a pivoted pawl for engaging the ratchet wheel to lock the same to the wick actuating shaft, and a reciprocating part on said shaft for actuating the pawl and for rotating said shaft.

11. In an oil burner, the combination with a burner tube and a wick actuating shaft, a spring actuated ratchet-wheel concentric with the shaft and loosely mounted relatively thereto, means for predetermining the rotation of the ratchet-wheel in one direction and limiting the rotation of said wheel to substantially a short distance in the wick raising direction to thereby fix the maximum height of the wick in its burning position, a pivotal pawl carried by the shaft adapted to engage the ratchet wheel to lock the same to the shaft, said pawl having an extension, a sleeve mounted on the upper end of the shaft and slidably mounted on the shaft, said sleeve having a disk with an opening through which the extension of the pawl projects whereby the pawl is operated by the reciprocal movements of said sleeve, said sleeve having an operating finger piece, a guide pin on the shaft passing through said sleeve, and means for locking the sleeve at the conclusion of its inward and outward reciprocation.

In testimony whereof I affix my signature.

HENRY W. BRENT.
